CLAIM

The ornamental design for a machine tool, as shown and described.

DESCRIPTION

1.-5. Machine tool

2.1 : Perspective

2.2 : Perspective

2.3 : Front

2.4 : Back

2.5 : Top

2.6 : Right

2.7 : Left

2.8 : Perspective

2.9 : Perspective

2.10 : Top view showing the claimed part

The broken lines in the drawings form no part of the claimed design; the dash-dotted lines in Figures 2.1-2.10 represent the unclaimed boundaries. Figures 2.8-2.10 are perspective

(Continued)

views showing the claimed portions of the machine tool with portions of the unclaimed subject matter removed for clarity.

1 Claim, 10 Drawing Sheets
